UNITED STATES PATENT OFFICE.

SCHUYLER N. NOLAN, OF RIVER FOREST, ILLINOIS.

INTERNAL-COMBUSTION ENGINE.

Application filed April 16, 1923. Serial No. 632,212.

This invention relates to improvements in internal combustion engines.

One object of the invention is to provide a simple and efficient internal combustion engine of the four cycle type, employing two cylindrical sleeves, or similar elements, which perform the functions of valves.

Another object of my invention is to provide an internal combustion engine of the character indicated, wherein large port openings for both in-take and exhaust are provided, and wherein a very quick opening of the exhaust port is had in order to minimize the back pressure during the exhaust stroke.

Another object of the invention is to provide a mechanism of the character indicated, wherein the stroke of the cylindrical sleeve valves is reduced to a minimum.

Still another object of the invention is to provide an internal combustion engine of the type indicated, wherein the cylinder head is provided with means co-acting with the sleeves adapted to overlap the ports in the sleeves, during the greater portion of the compression and expansion or explosion stroke of the piston, thereby preventing leakage and protecting the edges of the ports from the intense heat generated in the combustion space during the explosion stroke.

A still further object of the invention is to provide in an internal combustion engine of the character indicated, an arrangement whereby uniform cooling of the sleeves in the region of the ports is effected, thereby preventing an uneven expansion or warping of the sleeves.

Another object of the invention is to provide an internal combustion engine having the cylinder thereof provided with intake and exhaust port openings for the greater portion of the circumference thereof; thereby obtaining the maximum capacity of intake and exhaust openings.

Other objects and advantages of the invention will more clearly appear from the description and claims hereinafter following.

In the drawings forming a part of this specification, Fig. 1 is a vertical sectional view through the cylinder of an engine illustrating one form of the invention. Figs. 2 to 7 inclusive are enlarged, detail, vertical sectional views of portions of the cylinder head and sleeves, taken at the left hand side of Fig. 1, and illustrating the movements

of and different positions assumed by the sleeves at different stages of the operation. Fig. 8 is a vertical sectional view similar to Fig. 7, illustrating a modified form of sleeves. Figs. 9 and 10 are diagrammatic views illustrating the operation of the outer and inner sleeve-operating cranks, respectively. Fig. 11 is a vertical sectional view similar to Fig. 7, showing a further modification of sleeves. Fig. 12 is a vertical sectional view similar to Fig. 1 showing the upper end of the cylinder, and illustrating another form of the invention. Figs. 13, 14, 15, 16 and 17 are enlarged, detail, vertical sectional views through portions of the cylinder, sleeves and cylinder head, at the left side of Fig. 12, illustrating the movements of and positions assumed by the sleeves, at different stages of the operation. Fig. 18 is a transverse horizontal sectional view through the cylinder and sleeves corresponding to the plane of the exhaust ports, and passing through the port openings in the sleeves. And Figs. 19, 20, 21, 22 and 23 are diagrammatic views illustrating the different positions assumed by the cranks operating the inner and outer sleeves during the different stages of the operation illustrated in Figs. 13 to 17 inclusive, respectively.

The improved mechanism as illustrated in Figs. 1 to 7 inclusive, comprises a cylinder A; cylinder head B; piston C; connecting rod D; crank E; an outer sleeve F; an inner sleeve G; valve connecting rods H and J; and valve operating crank shaft K.

The cylinder A is fixed to the base portion of the engine, and is provided with diametrically opposite exhaust ports 1, and diametrically opposite in-take ports 2, the ports 1 and 2 extending entirely around the cylinder at the point of communication with the interior thereof as clearly shown in Fig. 18. The upper part of the cylinder A is provided with a surrounding water jacket as indicated at 12.

The upper part of the cylinder A is closed by the head B which is provided with an inwardly projecting portion 9 having a combustion chamber 10 formed therein. The cylinder head B is water cooled by providing the same with a water jacket as indicated at 11, and is also provided with a threaded opening 18, communicating with the combustion chamber 10 and adapted to receive the usual spark plug.

As clearly shown in Fig. 1, the projection 9 is provided with spring rings 14, and an annular space 19 is left between the side wall of the projection 9 and the inner wall 17 of the cylinder A, for a purpose herein-after described.

The piston C is of the usual construction and is adapted to reciprocate in the cylinder A, being connected to the crank shaft E by 10 means of the connecting rod D.

The sleeves F and G are of cylindrical form, and are slidably movable within the cylinder A, having their upper ends interposed between the projection 9 on the cylinder head and the inner wall 17 of the cylinder A by extending into the space 19. As clearly shown in Fig. 1, the sleeve G is telescoped within the sleeve F, is of greater length than the latter, and is adapted to 20 slidably receive the piston C.

The outer sleeve F is reciprocated within the cylinder through the medium of the connecting rod H, operated by the crank 16 of the crank shaft K. The inner sleeve G, which is adapted to reciprocate within the sleeve F, has the lower end thereof extended beyond the same, and is operated through the medium of the connecting rod J operated by the crank 15 of the crank shaft K. As 25 clearly shown in Figs. 1 to 7 inclusive, the sleeves F and G are provided with port openings 8 and 7 respectively, adapted to establish communication between the interior of the cylinder and the exhaust and in-take ports; during the operation of the engine. The port openings 8 of the sleeve F extend around the circumference thereof, as shown in Fig. 18, thereby, obtaining the maximum capacity of port opening. Each of the port 30 openings 8 is enlarged toward the inner side of the sleeve, being provided with a top wall comprising two horizontal shoulders 20 and 21, in different planes, connected by an inclined portion 22 and a bottom wall comprising two horizontal shoulders 23 and 24, in different planes, connected by an inclined portion 25. The port openings 7 of the inner sleeve G also extend around the circumference thereof, thereby providing a maximum amount of port opening. Each of the 35 ports 7 is enlarged towards the outer side of the sleeve G and is provided with a top wall comprising two horizontal shoulders 26 and 27, in different planes, connected by an inclined portion 28 and a bottom comprising two horizontal shoulders 29 and 30 in different planes, connected by an inclined portion 31.

The crank shaft K, through which the reciprocating sleeves are operated, is suitably geared with the main crank shaft E and driven at one-half of the crank shaft speed.

The operation of my improved valve mechanism, as illustrated in Figs. 1 to 7 inclusive, is as follows. At the beginning of

the upward movement of the piston C, during the exhaust stroke, the sleeves F and G are in the position shown in Fig. 2 with the shoulder 30 of the opening 7 in alinement with the lower face of the enlargement 9 of the cylinder head, and the shoulder 20 of the opening 8 in the sleeve F, in alinement with the upper wall of the exhaust port 1. During the upward movement of the piston C, in the exhaust stroke, the cranks 16 and 15 of the valve operating crank shaft K will effect movement of the sleeves F and G in the directions indicated by the arrows in Figs. 2, 3 and 4, the sleeve F moving upwardly during the initial portion of the exhaust stroke as indicated until the crank 15 reaches the vertical position, whereupon motion of the sleeve F will be reversed, and the same will move downwardly, as indicated by the arrow in Fig. 3. During this time 55 the sleeve G will move downwardly, and the shoulder 30 will move away from the projection 9, establishing communication between the exhaust port 1 and the interior of the cylinder, as clearly shown in Fig. 3. 60 During the further upward movement of the piston the sleeves F and G will be moved downwardly simultaneously, until the end of the exhaust stroke is reached, when the port 1 will be closed by the shoulder 20 of the sleeve F, as shown in Fig. 4, the shoulder 20 then being in alinement with the lower edge of the exhaust port. At the end of the exhaust stroke of the piston, the inner sleeve G will have reached its lowermost position, and upon further movement of the piston during the in-take stroke, the sleeve C will be moved upwardly as indicated by the arrow in Fig. 5, the sleeve F continuing in its downward movement. As the sleeve F moves downwardly, the lower shoulder 23 of the opening 8 will pass below the upper wall of the in-take port 2, and establish communication between the latter and the interior of the cylinder, as shown in Fig. 5. 65 During further movement of the piston in a downward direction, the sleeve G will continue to move upwardly and the sleeve F downwardly, as indicated by the arrows in Fig. 6, thereby increasing the capacity of 70 the intake opening. Movement of the sleeve F will continue in a downward direction, until the piston reaches the end of the in-take stroke and begins to travel upwardly, when the sleeves F and G will have reached 75 a relative position, where the shoulders 24 and 26 thereof are in alinement and cut off communication between the in-take port and the interior of the cylinder. During the subsequent upward movement of the piston 80 while compression is taking place, movement of the sleeve F will be reversed and both of the sleeves will be moved upwardly simultaneously as clearly shown in Fig. 7. During the further upward movement of the 85

sleeves F and G, the lower shoulder 30 of the port 7 of the sleeve G will pass beyond the lower face of the projection 9. As the sleeves travel upwardly during the remainder of the compression stroke, the portions of the sleeves carrying the port openings 7 and 8 will be entirely protected by being housed within the recess 8. During the greater portion of the expansion stroke, the sleeves F and G will move downwardly together, until they again reach the approximate position shown in Fig. 2, with the lower shoulder 30 of the port 7 in the sleeve G in alignment with the lower face of the projection 9 on the cylinder head, and the described cycle of operations is repeated.

The movement of the sleeve operating cranks 15 and 16, during in-take, compression, expansion and exhaust is graphically represented in Figs. 9 and 10. As shown in Fig. 9, the crank 16 which actuates the outer sleeve F is at position *a* when the exhaust port begins to open, and the sleeves F and G are in the position shown in Fig. 2. At the same instant, the crank 15, which actuates the sleeve G is in the position indicated by *e* in Fig. 10. During exhaust, the crank 16 travels from *a* to *b* and the crank 15 travels from *e* to *f*, sleeves F and G traveling as indicated in Figs. 2, 3 and 4. When the cranks 16 and 15 reach the positions *b* and *f*, respectively, the exhaust port will be completely closed, and the in-take port is about to open. As the crank 16 travels from *b* to *c*, and the crank 15 travels from *f* to *g*, in-take occurs, and the sleeves F and G are operated as shown in Figs. 5, 6 and 7. When the cranks 16 and 15 reach the positions *c* and *g*, respectively, communication will be completely cut off between the in-take port and the interior of the cylinder as shown in Fig. 7. During compression, the crank 16 will travel from *c* to *d*, and the crank 15 will travel from *g* to *h*, the sleeves F and G traveling from the positions shown in Fig. 7 to the positions shown in Fig. 1. During expansion, the crank 15 will travel from *d* to *a*, and the crank 16 will travel from *h* to *e*, the sleeves F and G moving from the position shown in Fig. 1 to the position shown in Fig. 2. From the preceding description, and upon reference to Figs. 9 and 10, it will be evident that the sleeves F and G are moved upwardly simultaneously during the entire compression stroke, and that the portion of the inner sleeve G in which the port 7 is located is within the annular recess 8 and between the projection of the cylinder head and the cylinder wall, during the entire time that the expansion takes place, thereby protecting the edges of the ports from the intense heat created in the cylinder during combustion. As the cylinder head and cylinder are both water

jacketed in the region of the opening 19, the sleeve G will also be cooled adjacent to port 7 during this time. It will be further evident that as the ports 8 and 7, each serve, as both in-take and exhaust ports, the sleeves F and G will also be cooled adjacent to these ports, after the exhaust gases have passed therethrough, by the cooling effect of the charge being drawn into the cylinder. By keeping the sleeves thus properly cooled in the region of the ports, the danger of undue expansion or warping of the sleeves is effectively prevented.

The modified form shown in Fig. 8 is in all respects similar to the form illustrated in Figs. 1 to 7 inclusive, with the exception that the outer sleeve M and the inner sleeve N, which correspond to the sleeves F and G respectively, are provided with ports 108 and 107 of a slightly different construction. The port 108 of the sleeve M is provided with a horizontal bottom wall 50, and a top wall, comprising two horizontal shoulders 51 and 52, in different planes, connected by an inclined portion 53, the portion 52, being in a plane above the portion 51, thereby providing the port 108 with a larger opening at the inner side of the sleeve than at the outer side thereof. The port 112 of the sleeve N is provided with a horizontal top wall 54, and a bottom wall, comprising two horizontal shoulders 55 and 56 in different planes, connected by an inclined portion 57, the portion 56 being in a plane above the portion 55 whereby, the port 107 is provided with a larger opening at the outer side of the sleeve N than at the inner side thereof.

The modified form shown in Fig. 9 is in all respects similar to the form illustrated in Figs. 1 to 7 inclusive, with the exception that the outer sleeve P, which corresponds to the sleeve F, is provided with a port 208 having horizontal top and bottom walls. The inner sleeve R is in all respects similar to the sleeve G, and is provided with a port 207 also corresponding in all respects to the port 7. The relative position of the sleeves M and N in Fig. 8 and the relative position of the sleeves P and R in Fig. 11 corresponds to the position of the sleeves F and G shown in Fig. 7, and the operation thereof is in all respects similar to the operation of the sleeves F and G of the form of the invention shown in Figs. 1 to 7 inclusive.

The form of the invention illustrated in Figs. 12 to 17 inclusive and Figs. 19 to 23 inclusive comprises, a cylinder A'; a cylinder head B'; a piston C'; an outer valve sleeve F' and an inner valve sleeve G'; in all respects similar to the construction shown in Figs. 1 to 7 inclusive, with the exception that the in-take and exhaust ports of the cylinder are reversed. As clearly shown in Fig. 12 the cylinder is

provided with exhaust ports 301 and in-take ports 302, the in-take ports being located above the exhaust ports. The sleeves F' and G' are provided with ports 308 and 307 in all respects similar to the ports 8 and 7 of the form of the invention shown in Figs. 1 to 7 inclusive. In Figs. 19 to 23, the different positions of the cranks which operate the outer and inner sleeves are dia-
 grammatically represented, corresponding to the different stages of the operation of the valve mechanism as shown in Figs. 13 to 17 inclusive, the crank indicated by 316 corresponding to the crank 16 and the crank indicated by 315 corresponding to the crank 15. In Fig. 13 the sleeves F' and G' are shown in the position assumed at the instant the exhaust stroke of the piston begins. At this time the cranks 315 and 316 will be in the position shown in Fig. 19. As the cranks rotate from the position shown in Fig. 19 to the position shown in Fig. 20, the outer sleeve F' will first move downwardly a short distance, until the crank 316 passes the dead center, whereupon it will begin to move upwardly until it reaches the position shown in Fig. 20 and the sleeve F' assumes the position shown in Fig. 14. During this time the sleeve G' will move downwardly as indicated by the arrows, opening the exhaust port as it moves, until the position shown in Fig. 14 is assumed thereby. As the cranks 316 and 315 travel from the position in Fig. 20 to the position in Fig. 21, the sleeve F' will move upwardly to the position shown in Fig. 15, closing the exhaust port 301. At the same time movement of the sleeve G' will be reversed, the same moving upwardly as indicated by the arrow. During the traveling of the cranks from the position shown in Fig. 21 to that shown in Fig. 22, in-take will begin, and the sleeves F' and G' will move upwardly in unison, the movement of the sleeve F' opening the in-take port 302 as indicated in Fig. 16. Upon further movement of the cranks from the position shown in Fig. 22 to the position shown in Fig. 23, the sleeve G' moving upwardly will cut off communication between the in-take port and the interior of the cylinder by the shoulder 330 of the port 307 passing beyond the lower face of the projection 309 of the cylinder head B'. When the crank 316 reaches the position shown in Fig. 23, the motion of the sleeve F' will be reversed and the same begins to move downwardly. The sleeve F' continues to move downwardly and again reaches the position shown in Fig. 13. The sleeve G' continues to move upwardly after effecting the closing of the in-take port until it reaches approximately the position shown in Fig. 12 when movement thereof is reversed. At this time expansion begins, and the sleeve G' continues to travel downward-

ly and again reaches the position shown in Fig. 13, which is the position assumed just prior to the opening of the exhaust port.

From the foregoing description, it will be evident that the lower shoulder 330 of the port 307 co-operates with the projection 319 on the cylinder head to effect both the opening of the exhaust port and the closing of the in-take port, that the lower shoulder 323 of the port opening 308 effects the closing of the exhaust port, that the shoulder 320 of the port 308 effects the opening of the in-take port, that the ports 316 and 315 are in communication in all positions assumed by the sleeves during their operation, and that both sleeves travel downwardly and in the same direction as the piston during the expansion stroke.

It will also be evident that the port 307 is protected from the intense heat created during combustion by being interposed between the projection 319 on the cylinder head and the wall 317 of the cylinder, during the entire time that the expansion takes place, in a manner similar to that described in connection with the form of the invention illustrated in Figs. 1 to 7 inclusive.

I have herein shown and described what I now consider the preferred manner of carrying out the invention, but the same is merely illustrative and I contemplate all changes and modifications that come within the scope of the claims appended hereto.

I claim:

1. In an internal combustion engine, the combination with a combustion chamber having in-take and exhaust ports; of means for establishing and closing communication between said ports and the interior of said chamber, said means including a pair of 100 movable elements, each provided with a port common to both in-take and exhaust, and a fixed member projecting into said combustion chamber and co-acting with the port of one of said elements to open and close 105 the same; and means for operating said elements.

2. In an internal combustion engine, the combination with a cylinder, having in-take and exhaust ports; of a valve sleeve 115 slideable within said cylinder, said sleeve having a port adapted to communicate alternately with the in-take and exhaust ports; a second sleeve telescoped within said first named sleeve and movable relatively thereto, said second named sleeve having a port common to both in-take and exhaust; a wall fixed to the cylinder and projecting into the second named sleeve and adapted to co-act with the port thereof to establish communication between the interior of the cylinder and the port of the first named sleeve; and means for operating said sleeves.

3. In an internal combustion engine, provided with a cylinder having intake and ex- 120

- haust ports, the combination with a cylindrical sleeve slidable within said cylinder and having a port common to both in-take and exhaust; of a second cylindrical sleeve 55
5 slideable within the first named sleeve and provided with a port common to both in-take and exhaust, and adapted to communicate with the port of said first named sleeve; means fixed to the cylinder projecting into
10 the second named sleeve adapted to co-act with the port thereof to establish communication between the exhaust port and the interior of the cylinder and close communication between the in-take port and the interior of the cylinder; and means for operating said sleeves.
4. In an internal combustion engine, the combination with a cylinder having intake and exhaust ports; of a piston within said cylinder; inner and outer sleeve valves 20 mounted to reciprocate within said cylinder, said sleeve valves having co-operating sets of ports adapted to be placed in communication with each other, and the port of the outer sleeve of each co-operating set of ports co-operating with both said intake and exhaust ports, the width of said ports in the sleeve valves being greater on their meeting faces than on their separated faces 25
25 whereby the required strokes of said sleeve valves are reduced for a predetermined period of communication between said ports.
5. In an internal combustion engine, the combination with a cylinder having intake and exhaust ports; of a piston within said cylinder; a pair of sleeve valves mounted to reciprocate within said cylinder, said sleeve valves having ports adapted to be placed in communication with each other 30
35 and said intake and exhaust ports, each of said ports of one sleeve being greater in width on one side of the sleeve than on the other side thereof.
6. In an internal combustion engine, the combination with a cylinder having intake and exhaust ports; of a piston within said cylinder; a pair of sleeve valves movably mounted within said cylinder, said sleeve valves having ports adapted to be placed 40
45 in communication with each other and with the exhaust and intake ports of the cylinder, said port of each sleeve being of greater area on one side of said sleeve than on the other side thereof, said section of greater
- area of said port extending for an appreciable distance inwardly of said sleeve; and means for moving said sleeves.
7. In an internal combustion engine, the combination with a cylinder having intake and exhaust ports spaced axially of the cylinder, the exhaust port being disposed at the outer end of the cylinder; a piston working within the cylinder; a sleeve movably mounted within the cylinder and having a port adapted to register alternately with the intake and exhaust ports; a second sleeve movably mounted within the first named sleeve and provided with a port common to both intake and exhaust and adapted to communicate with the port of the first named sleeve; means within the cylinder projecting into the last named sleeve adapted to cooperate with the port thereof during compression and expansion to close the same; and means cooperating with the piston for effecting operation of the sleeves. 55
60
65
70
75
8. In an internal combustion engine, the combination with a cylinder provided with intake and exhaust ports; of a sleeve slidably mounted within said cylinder and provided with a port common to both intake and exhaust; a second sleeve slidably telescoped within the first named sleeve and also having a port common to both intake and exhaust, and adapted to communicate with the port of the first named sleeve; and means projecting into the second named sleeve and having an edge adapted to cooperate with the port of the last named sleeve to establish communication between the exhaust port and the interior of the cylinder and close communication of the intake port and the interior of the cylinder, said means being adapted to overlap the port of the last named sleeve during expansion and compression; a piston working within the last named sleeve; and means cooperating with the piston and with the respective sleeves for operating the latter, said last named means operating to move the first named sleeve in a direction opposite to the movement of the piston during the intake stroke. 80
